United States Patent Office

Des. 181,881

Patented Jan. 7, 1958

181,881

HAND LUGGAGE OR SIMILAR ARTICLE

Benjamin Rosen and Albert Rosen, Seattle, Wash., assignors to Durabilt Luggage Manufacturing Company, Seattle, Wash.

Application February 18, 1957, Serial No. 44,900

Term of patent 7 years

(Cl. D87—5)

FIG 1

Figure 1 is a perspective view, showing the new design of our hand luggage or similar article;

The dominant feature of this design resides in the V-shaped ornamentation on the faces of the hand luggage or similar article.

We claim:

The ornamental design for hand luggage or similar article, as shown and described.
